ATTORNEYS

UNITED STATES PATENT OFFICE.

CHARLES C. OVERTON, OF CONEY ISLAND, NEW YORK.

DESIGN FOR A DISH.

SPECIFICATION forming part of Design No. 19,690, dated March 4, 1890.

Application filed January 17, 1890. Serial No. 337,242. Term of patent 7 years.

To all whom it may concern:

Be it known that I, CHARLES C. OVERTON, of Coney Island, in the county of Kings and State of New York, have invented and produced a new and original Design for Dishes, of which the following is a full, clear, and exact specification.

My new design is fully illustrated in the accompanying drawings, to which reference is made, and in which—

Figure 1 is a perspective view of my newly-designed dish, and Fig. 2 a sectional elevation of the same.

The body of my newly-designed dish is circular and the bottom *a* is flat. The outer surface of the body exhibits the opposite diverg-

ing lines *b b*, which meet the bottom *a* at an obtuse angle, and these lines *b b* merge into the short lines *c c*, which are parallel with each other and stand at right angles to the 20 plane of the bottom *a*. The short vertical lines *c*, meeting the diverging lines *b*, form the circumferential line or angle *d*. The interior of the dish exhibits diverging lines *e e*, which merge into the concaved bottom *f*. 25

I claim—

The design for a dish, substantially as herein shown and described.

CHAS. C. OVERTON.
